UNITED STATES PATENT OFFICE

ARNOLD BERNSTEIN, OF HAMBURG, GERMANY

APPARATUS FOR RAISING SHIPS' CARGOES

Application filed July 25, 1927, Serial No. 208,373, and in Germany April 25, 1927.

In the transference of ships' cargoes use has hitherto been made of ordinary ship's tackle or crane tackle, which necessitates the packages to be handled being actually 5 grabbed or laid hold of by the tackle and consequently damaged, especially as the goods cannot be prevented from swinging when hanging from the crane.

It is the object of the present invention to 10 avoid the possibility of damage to the packages of cargo to be handled. For this purpose a special loading platform for raising the cargo is provided on the ship; more particularly a loading platform such as shown 15 at *a* (see Figure 1) guided vertically against the outer shell of the ship.

With reference to the accompanying drawings:

Fig. 1 represents a vertical section of a 20 ship and in combination therewith a side elevation of the improved device for raising the cargo;

Fig. 2 shows a side view of the ship and 25 in combination therewith a front elevation of the loading platform.

The said platform *a* is attached to a frame *b* which is apertured and is provided with guide rollers and which may, if desired, be pivoted at *c* so as to be adapted to fold back 30 on to the upper deck.

The platform is so connected to the guide frame by the supporting struts *d* that it can be held in an approximately horizontal position relatively to the supporting frame but, 35 in any case, is inclined slightly towards the side of the ship rather than in the opposite direction. The rollers of the guiding and supporting frame run in guide bars *e*, which are attached vertically to the ship's side for 40 instance, by means of flat socket plates fixed on the side of the ship and adapted to receive corresponding flat pins provided on the lower end of the guide bars *e*. This method of attachment is preferable because the vertical 45 bars *e*, as also the frame itself, can only be advantageously placed on the outside of the ship when she is discharging or taking in cargo. For this purpose the guide bars *e* require to be attached at top and bottom only. 50 If they are fixed in the above mentioned sock-

ets at the bottom, the attachment at the top to the upper deck of the ship does not present the slightest technical difficulty. The guide bars may be lifted into position with the aid of the ordinarily existing ship's tackle and 55 crane devices, in which case special eyes for the attachment of the crane hooks of the hoisting gear may advantageously be provided to facilitate guiding into position the load-raising platform or the various parts 60 thereof.

A lifting tackle *f* attached above the guide frame enables the above described platform for raising the load to be moved up and down vertically with aid of a windlass (one of the 65 ordinary ship's winches or a special winch provided for this purpose), so that, with the aid of this platform the goods can be raised from the level of the quay to the level of the 70 upper deck of the ship without any risk of their being damaged and they may then be easily transferred on to the deck. Valuable goods, such as motor cars for example, are run horizontally from the quay on to the 75 platform, are then raised vertically without swinging movement of any kind to the deck of the ship and run (again horizontally) on to the ship's deck whence they can be transferred without damage (by means of the apparatus described in a prior application Ser. 80 No. 67,897) to the hold of the vessel and securely stowed therein.

As stated, the platform can be removed from the outside of the ship while the latter is in motion; thus, for example, it may be 85 turned down, together with the upper parts of the guiding device, on to the deck, as shown in Fig. 1. For this purpose the platform must be made to fold at *c* with the upper part of the guiding device and the supporting arms *d* must also be capable of being detached or collapsed. The guide bars, as already explained in detail above, may be wholly or partially detachable from the side 90 of the ship and can be hoisted by the ordinary ship's loading gear on to the deck and stowed there.

The details of construction may be modified in many and various ways without departing from the fundamental idea of the in- 100

vention, which consists in attaching to the side of a ship a loading platform similar in construction to a lift and adapted to move vertically.

It is, further, obvious that the means for attaching the loading platform may be so arranged that they can be applied at various points on the outside of the ship, according to the nature of the place where she is berthed for the time being, while, if necessary, the entire structure may be arranged to slide along the ship's side, for the purpose of locating it at the desired point on the ship according to the position of her berth and 15 how she happens to be lying.

All these modifications are easy to carry out when the idea on which the invention is based is explained and all of them are to be understood to fall within the scope of the 20 present invention.

The platform may be so constructed that the goods to be loaded can be brought on to the platform at right angles to the central plane of the ship and it may also obviously 25 be so constructed that the goods to be loaded can be brought on to the said platform in a direction parallel to the said central plane. No difference in the use of the invention is occasioned thereby.

30 In the drawings the first mentioned constructional form of the invention is shown, that is to say, the frame *b* may be opened such as to allow the load to be brought on to the platform *a* at right angles to the central 35 plane of the ship.

Having now particularly described and ascertained the nature of my said invention and in what manner the same is to be performed I declare that what I claim is:

40 1. In an apparatus for raising cargoes for ships, vertical guide bars adapted to be arranged on the outer shell of a ship, a loading platform, and means carrying said loading platform and movable on said guide bars, 45 said means including a frame apertured to afford horizontal access from the platform to the ship and vice versa.

2. In an apparatus for raising cargoes for ships, vertical guide bars adapted to be arranged on the outer shell of a ship, a loading 50 platform, and means carrying said loading platform and movable on said guide bars, said means including a frame apertured to afford access from the platform to the ship 55 and vice versa, and means permitting said platform to be folded over the top of the upper ship deck.

3. In an apparatus for raising cargoes for ships, vertical guide bars adapted to be arranged on the outer shell of a ship, a loading 60 platform, and means carrying said loading platform and movable on said guide bars, said means including a frame apertured to afford access from the platform to the ship 65 and vice versa, the guide bars, frame and

platform having joints permitting the platform to be folded over the upper ship deck.

4. In an apparatus for raising cargoes for ships, vertical guide bars adapted to be arranged on the outer shell of a ship, a loading platform, and means carrying said loading platform and movable on said guide bars, said means including a frame apertured to afford horizontal access from the platform to the ship and vice versa, and means permitting 75 said platform to be removed.

5. In an apparatus for raising cargoes for ships, a loading platform, vertical guide bars in the platform, means for detachably securing the guide bars to the shell of a ship, a device carrying the platform, said device including a frame movable vertically on said guide bars and having an opening permitting horizontal access from the platform to the ship and vice versa, and means permitting 80 folding of the platform and the upper portions of the guide bars upon a ship deck.

In testimony whereof I affix my signature.

ARNOLD BERNSTEIN.
